United States Patent Office.

ROBERT FARIES, OF INDIANAPOLIS, INDIANA.

Letters Patent No. 79,219, dated June 23, 1868.

IMPROVED SUPPLEMENTAL JAW FOR WRENCHES.

The Schedule referred to in these Letters Patent and making part of the same.

TO ALL WHOM IT MAY CONCERN:

Be it known that I, ROBERT FARIES, of Indianapolis, in the county of Marion, and State of Indiana, have invented a new and improved Applicable Wrench-Jaw; and I do hereby declare that the following is a full, clear, and exact description thereof, which will enable others skilled in the art to make and use the same, reference being had to the accompanying drawings, forming part of this specification.

This invention relates to a wrench-jaw of wedge-form, to be used with the common screw or other wrenches, for pipes, round bolts, &c., which, when applied to the work, (pipe, &c.,) and the wrench pulled in the proper direction, tightens on the work, and becomes tighter the more force is applied.

The present invention consists, principally, in curving said applicable jaw in its length, and providing a loop in the end of the same, the object of which will be hereafter stated, with other advantages.

In the drawings—

Figure 1 is a common screw-wrench, A, and pipe, B, and applicable jaw, C, as applied when in use.

Figure 2 is the face or side of the applicable jaw, which comes in contact with the work when in use.

Similar letters of reference denote like parts.

In fig. 1, the applicable jaw C will be seen to be taper or wedge-shape in its length, and curved in the same direction, having a bearing on the jaw of the wrench a on only a small part of its length, which is directly opposite to the point of contact with the pipe B, and in line with the force applied. It will be also seen that the face of the jaw C has teeth, b, cut across it, which teeth, coming in contact with work, cut into it and prevents slipping.

A hole is drilled through the corner of the jaw C at e, which forms a loop into which the chain d is hooked, the other end of which is hooked into a similar loop in the jaw a at e, which is for the purpose of keeping jaw C from dropping when detached from the work. But as it is the object for this improved jaw to be suitable for any common wrench, as now used, without any work necessary to be done to it, I will state that it is not absolutely necessary that the loop e be made, it would only be more convenient if it were there, which, however, almost any mechanic could do for himself.

In case the operator were working on a scaffolding, or in a well, or any place where there would be danger of losing it if dropped, it might be secured to the wrench, or to the operator's wrist, with a bit of string or wire, and answer the same purpose, if not so well.

This improved jaw may be made of either cast steel or cast iron chilled. The medium size of these jaws will be about as follows, to wit, seven-eighths of one inch wide, by one and one-quarter of one inch long, and about one-eighth of one inch thick on the thin end, and thick enough on the other end to give a taper of about one-quarter of one inch to one inch in length.

Now I am aware that wedge-shaped attachments to the common wrench have been made and used for the same purpose of the jaw I claim, but none of them are near so good. Some of the advantages of the within-described jaw I will state as follows, to wit: First, it being curved, as described, it presents a smaller surface, and is in better shape to pass over any unevenness on jaw a of the wrench, which being the case, it moves easier and gripes the work tighter than if it were straight, and is not so liable to roll the work out and strain the wrench; second, it having no projections that fit into or over any part of the wrench, a medium size is suitable for various-sized wrenches, without anything being done to the wrench; third, it is small and neat, and may be carried attached to the key-ring or fob-chain of the mechanic, and be always at hand when wanted for use, the chain being attached to it partly for that purpose; fourth, it can be made and sold much cheaper than others.

Now I do not wish to claim the within-described wrench-jaw, in combination with the wrench, that being represented in the drawings, for the better illustration of the invention. Suitable wrenches already exist, and are manufactured by others; consequently, under existing circumstances, the within-described applicable wrench-jaw is a useful article of itself; therefore,

What I claim as new, and desire to secure by Letters Patent, is—

The applicable wrench-jaw, when made substantially as described, as an article of manufacture.

ROBERT FARIES.
